EDGE GRINDING MACHINE

Henry O. Kranich, Toledo, Ohio, assignor to Libbey-Owens-Ford Glass Company, Toledo, Ohio, a corporation of Ohio

Application June 22, 1938, Serial No. 215,098

7 Claims. (Cl. 51—96)

The present invention relates to grinding machines in general and more particularly to the type of machine disclosed in the patent to Joseph P. Crowley, 2,046,060, June 30, 1936, for rounding and/or finishing the edges of sheets or plates of glass and the like.

Briefly, the machine disclosed in the above patent embodies a rotary grinding wheel positioned to rotate about a substantially horizontal axis, means mounted above said wheel for supporting a plurality of glass sheets to be ground on edge in a substantially vertical position, and means for rocking said supporting means to move the glass sheets backward and forward, with the edges thereof to be ground over and in engagement with the grinding wheel, said supporting means being mounted in such a manner that it is capable of free vertical floating movement during the rocking thereof depending upon the contour of the sheet edges being ground.

This invention constitutes an improvement upon the type of grinding machine disclosed in said patent and contemplates the provision of means for maintaining the glass sheets in proper engagement with the grinding wheel during the grinding operation whereby to facilitate and improve the grinding action so that the sheet edges being treated will be evenly and uniformly ground throughout.

An important object of the invention is the provision of novel means engaging the outer edges of the glass sheets for applying pressure thereto to urge the said sheets inwardly and maintain the inner edges thereof being ground in proper engagement with the grinding wheel during the rocking movement of the sheet supporting means.

Another important object of the invention is the provision of novel means for mounting and actuating the pressure means so that it will be automatically brought into engagement with the glass sheets and subsequently automatically moved out of engagement therewith when the sheet supporting means reaches predetermined positions in its rocking movement, to the end that pressure will be applied to the glass sheets only during such time as pressure may be actually required.

Other objects and advantages of the invention will become more apparent during the course of the following description, when taken in connection with the accompanying drawings.

In the drawings, wherein like numerals are employed to designate like parts throughout the same:

Fig. 1 is a side elevation of a grinding machine constructed in accordance with the present invention;

Fig. 2 is an end view thereof;

Figs. 3 and 4 are side views showing two different positions assumed by the sheet supporting means and pressure means during the grinding operation; and

Figs. 5 and 6 are diagrammatic views showing respectively the position of the glass sheet when the pressure is initially applied to the outer edge thereof and the position of said sheet at substantially the point where the pressure is removed therefrom.

Referring now to the drawings, the numeral 10 designates a vertical grinding wheel mounted to rotate about a horizontal axis and provided in its periphery with a plurality of grooves 11 within which the edges of the sheets or plates of glass or the like to be ground are adapted to be received. The grinding wheel 10 is received within a receptacle 12 adapted to contain a suitable abrasive material through which the lower portion of said wheel is adapted to run in a manner well known in the art. The top of 20 said receptacle is provided with a slot through which the upper portion of the grinding wheel projects.

The means for supporting the glass sheets to be treated comprises a holder or cradle designated in its entirety by the numeral 13, said holder being mounted above the grinding wheel 11 for free vertical and rocking movement. The work holder 13 comprises a pair of spaced, vertical side members 14 and 14' between which a 30 plurality of glass sheets 15 to be ground are adapted to be received, said sheets being disposed in a vertical position and the said side members being so shaped that the curved edges or corners 16 of the glass sheets to be treated 35 project therebeyond as clearly illustrated so that upon rocking of the work holder, the said edges will be moved backward and forward over and in engagement with the grinding wheel 10.

Arranged transversely between and carried by 45 the side members 14 and 14' of the work holder, adjacent the upper end thereof, are a plurality of horizontally aligned rollers 17, while arranged transversely between said side members adjacent the opposite or lower ends thereof are a plurality of similar rollers 18, said rollers 17 and 18 being adapted to receive the glass sheets 15 therebetween and to maintain them in proper position during the grinding operation. The said rollers 17 and 18 are preferably provided with a 50 55

plurality of grooves 19 and 20 respectively which align with the grooves 11 in grinding wheel 10 and within which grooves the corresponding edges of the glass sheets are adapted to be received.

Also positioned between and carried by the side members 14 and 14' of the work holder 13 are the rectangular plates 21 and 22 respectively, said plates being disposed at substantially right angles relative to one another and having grooves 23 and 24 respectively which register with the grooves in rollers 17 and 18 and are adapted to receive the adjacent edges of the glass sheets 15 therein.

Secured to the outer surfaces of the side members 14 and 14' of the work holder and extending diagonally thereof are elongated plates 25 and 26 respectively, to which are pivotally connected the inner ends of a pair of substantially horizontal, parallel supporting arms 27 and 28 respectively as indicated at 29 and 30. The supporting arms 27 and 28 are also freely mounted intermediate their ends upon a horizontal shaft 31 passing transversely through a block 32 supported upon the top of receptacle 12. The outer ends of the arms 27 and 28 are preferably bent inwardly toward one another and suspended therefrom are a plurality of weights 33, said weights being hung upon an eye bolt 34 attached at its upper end to the supporting arms by a transverse pin or the like 35. The weights 33 are provided to counterbalance the work holder 13 so that the glass sheets being ground normally rest more or less freely upon the grinding wheel, although the weights may be increased or decreased as desired.

Fixed upon the shaft 31, at one end thereof, inwardly of supporting arm 27 is a bell-crank lever 36 comprising the two angularly disposed portions or legs 37 and 38. Pivoted to the outer end of leg 37 of the bell-crank lever as at 39 is one end of a substantially horizontal connecting rod 40 pivotally connected at its inner end as at 41 to the plate 25 beneath supporting arm 27. Keyed to the opposite end of shaft 31, inwardly of supporting arm 28, is a lever (not shown) but which is similar to and extends parallel with the leg 37 of bell-crank lever 36. Pivotally connected to the outer end of this lever is one end of a substantially horizontal connecting rod 42 extending parallel with connecting rod 40 and being pivotally connected at its inner end as at 43 to the plate 26 beneath supporting arm 28.

Pivoted to the outer end of leg 38 of bell-crank lever 36 as at 44 is the upper end of a substantially vertical pitman 45. The pitman 45 is pivotally connected at its lower end as at 46 to a crank 47 keyed to a horizontal shaft 48, said shaft being driven from a motor 49 through a suitable chain and sprocket drive or the like 50 and reduction gearing located in the housing 51. Upon rotation of the shaft 48, the pitman 45 will be given a substantially vertical upward and downward motion to effect the turning of the horizontal shaft 31 first in one direction and then the other. This will impart a substantially horizontal forward and backward motion to the connecting rods 40 and 42, which will cause the work holder 13 to be rocked about the pivotal points 29 and 30, thereby causing the glass sheets 15 to be moved backward and forward with the curved edges 16 thereof to be ground over and in engagement with the grinding wheel 10.

In operation, and when it is desired to grind the curved edges or corners 16 of a plurality of sheets of glass 15, the work holder 13 is first

moved to the position illustrated in Fig. 1, at which time the pitman 45 is at substantially the extreme limit of its upward movement, while the connecting rods 40 and 42 are in retracted position. The glass sheets to be ground are then inserted horizontally into the outer open end of the holder between the upper and lower rollers 17 and 18, the upper edges *a* of the said sheets being received within the grooves 19 in rollers 17 while the bottom edges *b* thereof are received within the grooves 20 in rollers 18 and likewise within the grooves 24 in plate 22. The glass sheets are moved inwardly until the inner edges *c* thereof abut the plate 21 and are received within the grooves 23 formed therein.

After the glass sheets have been properly positioned, the motor 49 is placed in operation to rotate shaft 48 and draw the pitman 45 downwardly, this movement of the pitman causing the shaft 31 to be rocked in a counter-clockwise direction to impart a forward movement to the connecting rods 40 and 42. This forward movement of the connecting rods will cause the work holder to be also rocked in a counter-clockwise direction about its pivotal points 29 and 30 and 25 during the turning of the said work holder, the curved edges 16 of the glass sheets will be moved over and in engagement with the grinding wheel 16, as shown in Fig. 3, being received within the grooves 11 thereof. The grinding wheel is being simultaneously driven preferably in the opposite direction. The work holder is turned approximately 90 degrees and at the limit of its backward movement will assume substantially the position illustrated in Fig. 4, at which time 35 the glass sheets will be supported by the plate 21.

When the work holder is in this position, the crank 47 will have completed approximately one-half a revolution so that upon continued turning of the said crank, the pitman 45 will be started upwardly. This will cause the shaft 31 to be rocked in a clockwise direction to effect backward movement of the connecting rods 40 and 42, such movement causing the work holder 13 to be rocked in a clockwise direction to return it 45 to its starting position shown in Fig. 1.

Upon rocking movement of the work holder 13, the said holder will also be permitted to simultaneously move freely vertically depending upon the curvature of the sheet edges being ground. This is due to the fact that the supporting arms 27 and 28 are freely mounted upon shaft 31. With the above construction, curved edges of different contours can be readily and conveniently ground upon the machine. This renders the machine capable of a wide use and permits the grinding of a plurality of glass sheets simultaneously, with a minimum effort and attention on the part of the operator. Ordinarily, it will be found that one backward and forward rocking movement of the work holder is sufficient to effect the desired grinding of the glass sheets.

I have found, as a result of the commercial use of this type of machine by the assignee company, that there is sometimes a tendency for the grinding of the edges or corners 16 of the glass sheets to be more or less ununiform or uneven resulting in rough spots at certain points on the sheet edges. This, I believe, is due to the fact that the work holder is ordinarily counter-balanced so that the glass sheets rest more or less freely upon the grinding wheel, coupled with a tendency for the glass sheets to be forced outwardly within said work holder during rocking movement thereof. This tendency toward uneven or ununiform

grinding has been completely overcome by the use of my invention which contemplates the provision of means for engaging and applying pressure to the outer edges *d* of the glass sheets *15* during rocking movement of the work holder to urge the said sheets inwardly and maintain the inner edges *16* thereof being ground in proper engagement with the grinding wheel. Such pressure means consists briefly of a freely rotatable pressure roll operatively connected with the work holder and actuated by movement thereof, together with means for supporting said pressure roll and causing it to be automatically brought into engagement with the glass sheets and subsequently removed therefrom when said work holder reaches predetermined positions in its rocking movement. In other words, the pressure is adapted to be applied to the outer edges of the glass sheets only during such time as pressure may be actually required, and which has been previously determined by the curvature of the sheet edges to be ground.

With reference to the drawings, the novel pressure means comprises a pair of substantially rectangular, flat metal plates *52* and *53* arranged outwardly of and secured to the side members *14* and *14'* respectively of the work holder *13*. The plates *52* and *53* project upwardly beyond the work holder and each plate is provided at its upper end with a relatively long transverse slot *54* which is normally disposed in a substantially horizontal position. The numerals *55* and *56* designate a pair of inverted U-shaped supports straddling the work holder *13*, and each comprising the vertical side members *57* and *58* secured at their lower ends to brackets *59* and *60* respectively carried by the receptacle *12* and connected at their upper ends by the horizontal top member *61*.

Arranged inwardly of and carried by the side members *57* of the supports *55* and *56* is a horizontally disposed vertical cam plate *62*, the upper edge of which is suitably shaped or cammed to form the desired contour. As shown by way of example, the upper edge of the cam plate *62* is provided with a concavely curved portion *63* which extends from the forward end of the plate to a point adjacent the rear end thereof where it terminates in a horizontal portion *64*. It will of course be appreciated, that when grinding glass sheets having different types of curvatures, the contour of the upper edge of the cam plate is adapted to be varied accordingly. The cam plate *62* is carried by bolts *65* and *66* which pass through vertical slots *67* and *68* in the side members *57* of the supports and have threaded thereupon nuts *69* and *70* respectively. Encircling each bolt *65* and *66* inwardly of the respective side member *57* is a collar *71* for spacing the cam plate *62* the desired distance from said side members. Due to the provision of the slots *67* and *68*, the cam plate *62* can be adjusted vertically as desired. Arranged inwardly of the side members *58* of the supports *55* and *56* is a second cam plate *72* which is disposed directly opposite cam plate *62* and is similar thereto, especially as regards the contour of its upper edge. Thus, the curved and straight horizontal portions *63'* and *64'* of cam plate *72* are similar to and in horizontal alignment with the curved and straight horizontal portions *63* and *64* of cam plate *62*. The cam plate *72* may be secured to the side members *58* in the same manner that cam plate *62* is secured to side members *57*.

Extending between the plates *52* and *53* and

passing through the slots *54* therein is a bolt *73* having a nut *74* threaded upon one end thereof to secure the said bolt at the desired position within the slots *54*. Mounted upon the bolt *73* between the plates *52* and *53* is a collar *75* and loosely carried thereby is an inverted, substantially U-shaped carrier *76* comprising the substantially parallel arms *77* and *78* and the connecting outer portion *79*. Positioned between the arms *77* and *78*, adjacent the outer ends thereof, is the rotatable pressure roll *80* freely rotatable upon a transverse pin *81* carried by said arms. This pressure roll is preferably of relatively soft rubber, rubber composition, or the like. Also carried at the outer end of the carrier *76* is a weight *82* which normally tends to urge the pressure roll *80* downwardly and which also provides the desired pressure when the said roll engages the glass sheets. Carried by the arms *77* and *78* and passing therethrough is a transverse rod *83*, said rod projecting beyond the said arms and carrying at its opposite ends the supporting rollers *84* and *85* which are adapted to ride along upon the cammed upper edges of the cam plates *62* and *72* respectively. These rollers are held upon the rod *83* by nuts *86* and *87* while collars *88* and *89* may be mounted upon said rod between the rollers and arms *77* and *78* to maintain the said rollers in proper position relative to the cam plates *62* and *72*.

Upon reference to Fig. 1, it will be seen that when the work holder *13* is disposed in its initial starting position, the rollers *84* and *85* will be located adjacent the forward ends of the cam plates *62* and *72* and when in this position, the pressure roll *80* will be out of the way so as not to interfere with the placing of the glass sheets *15* to be ground in the work holder. After the glass sheets have been properly positioned within the work holder, the motor *49* is placed in operation to rock the said work holder in a counter-clockwise direction as explained above. When this is done, plates *52* and *53* of the pressure means will be similarly rocked whereupon the arms *77* and *78* of carrier *76* will first be moved to a substantially horizontal position as shown in Fig. 3. Upon continued rocking movement of the work holder, the rollers *84* and *85* will be drawn rearwardly over the concavely curved portions *63* and *63'* of cam plates *62* and *72* which will cause the pressure roll *80* to be lowered to engage the outer edges *d* of the glass sheets as illustrated in Fig. 5. As the work holder approaches the end of its rocking movement, the rollers *84* and *85* will pass from the curved surfaces *63* and *63'* up onto the flat horizontal portions *64* and *64'* as shown in Fig. 6, thereby raising the pressure roll *80* off the glass sheets as illustrated in Fig. 4.

In Figs. 3 and 4 is shown respectively the position of the pressure roll *80* and associated parts before the said roll engages the glass sheets and after it is moved out of engagement therewith, while Figs. 5 and 6 designate respectively the points where the pressure roll initially engages the outer edges of the glass sheets *d* and the point where the said roll is adapted to move from engagement therewith. As the glass sheets are rocked from the position shown in Fig. 5 to the position shown in Fig. 6, the pressure roll *80* will be held downwardly in engagement with the outer edges *d* of the glass sheets by the weight *82* and thereby hold the inner curved edges *16* of the sheets in proper engagement with the grinding wheel so as to facilitate the grinding.

action and obtain a more even and uniformly ground surface.

I have discovered that when grinding different types of curvatures, it is necessary that the pressure be applied to the glass sheets at different points, and therefore in the grinding of different curvatures, cam plates having differently shaped upper edges or cam surfaces are used so that the pressure will be applied to and subsequently removed from the glass sheets when the work holder reaches predetermined positions in its rocking movement. In other words, when grinding certain types of curves, it may be necessary for the pressure to be applied to the outer edges 10 of the glass sheets throughout substantially the entire grinding operation, whereas when grinding other types of curves, it may be necessary for the pressure to be exerted upon the sheets only during a very small portion of the rocking 15 movement of the work holder. The extent to which the pressure roll 80 is caused to exert pressure upon the outer edges *d* of the glass sheets 20 can be readily controlled by use of different cam plates. The pressure will be applied to the 25 glass sheets in the same manner upon rocking of the work holder in a clockwise direction to return it to starting position since the bolt 13 is not slidable in the slots 54 but instead is secured in a fixed position therein. The slots 54 are 30 provided to permit initial horizontal adjustment of the pressure roll 80 relative to the work holder 13 depending upon the type of curvature being ground and the shape and size of the cam plates 35 62 and 72.

35 It is to be understood that the form of the invention herewith shown and described is to be taken as the preferred embodiment of the same, and that various changes in the shape, size and arrangement of parts may be resorted to without departing from the spirit of the invention or the 40 scope of the subjoined claims.

I claim:

45 1. In a machine for grinding the curved edge of a glass sheet or plate, a rotary grinding wheel positioned to rotate about a substantially horizontal axis, means arranged above said wheel for supporting the glass sheet to be ground on edge in a vertical position, means for rocking said supporting means and sheet carried thereby 50 to move the curved edge of the sheet to be ground over and in engagement with said grinding wheel, means for applying pressure to the outer edge of the glass sheet to maintain the inner edge thereof in engagement with said grinding wheel during 55 rocking movement of said supporting means, and stationary cam means for causing said pressure means to be moved into engagement with the sheet and for subsequently removing the same therefrom when the said supporting means 60 reaches predetermined positions in its rocking movement.

65 2. In a machine for grinding the curved edge of a glass sheet or plate, a rotary grinding wheel positioned to rotate about a substantially horizontal axis, means arranged above said wheel for supporting the glass sheet to be ground on edge in a vertical position, means for rocking said supporting means and sheet carried thereby to move the curved edge of the sheet to be ground over 70 and in engagement with said grinding wheel, and means connected to and actuated by said supporting means during rocking movement thereof for applying pressure to the outer edge of the glass sheet to hold the inner edge thereof in engagement with said grinding wheel.

75 3. In a machine for grinding the curved edge of a glass sheet or plate, a rotary grinding wheel positioned to rotate about a substantially horizontal axis, means arranged above said wheel for supporting the glass sheet to be ground on edge in a vertical position, means for rocking said supporting means and sheet carried thereby to move the curved edge of the sheet to be ground over and in engagement with said grinding wheel, pressure means connected to and actuated by said supporting means during rocking movement thereof for engaging the outer edge of the glass sheet to hold the inner edge thereof in engagement with said grinding wheel, and means for supporting said pressure means and for causing the same to be moved into engagement with the sheet and subsequently removed therefrom when said supporting means reaches predetermined positions in its rocking movement.

4. In a machine for grinding the curved edge 20 of a glass sheet or plate, a rotary grinding wheel positioned to rotate about a substantially horizontal axis, means arranged above said wheel for supporting the glass sheet to be ground on edge in a vertical position, means for rocking said supporting means and sheet carried thereby to move the curved edge of the sheet to be ground over and in engagement with said grinding wheel, a 25 pressure roll adapted to engage the outer edge of the glass sheet for holding the inner edge thereof 30 in engagement with said grinding wheel during rocking movement of the supporting means, means for pivotally connecting said pressure roll to said supporting means so that the said roll is 35 actuated by the said supporting means upon rocking movement thereof, and cam means for supporting said pressure roll and for causing it to engage the sheet and to be subsequently removed therefrom when said supporting means reaches predetermined positions in its rocking 40 movement.

5. In a machine for grinding the curved edge of a glass sheet or plate, a rotary grinding wheel positioned to rotate about a substantially horizontal axis, means arranged above said wheel for 45 supporting the glass sheet to be ground on edge in a vertical position, means for rocking said supporting means and sheet carried thereby to move the curved edge of the sheet to be ground over and in engagement with said grinding wheel, a 50 pressure roll adapted to engage the outer edge of the glass sheet for holding the inner edge thereof in engagement with said grinding wheel during rocking movement of the supporting means, arms carrying said pressure roll at their 55 outer ends and being pivotally connected at their inner ends to said supporting means so that the said roll is actuated by the said supporting means upon rocking movement thereof, a pair of spaced substantially horizontal cam plates mounted 60 above said supporting means and having cammed upper edges, and rollers carried by said arms and supported upon the cammed upper edges of said cam plates for causing the said pressure roll to engage the sheet and to be subsequently removed 65 therefrom when said supporting means reaches predetermined positions in its rocking movement.

6. In a machine for grinding the curved edge of a glass sheet or plate, a rotary grinding wheel 70 positioned to rotate about a substantially horizontal axis, means arranged above said wheel for supporting the glass sheet to be ground on edge in a vertical position, means for rocking said supporting means and sheet carried thereby to move the curved edge of the sheet to be ground over 75

and in engagement with said grinding wheel, pressure means mounted above the sheet supporting means, and means actuated by said sheet supporting means upon rocking movement thereof for causing said pressure means to apply pressure to the outer edge of the glass sheet to maintain the inner edge thereof in engagement with said grinding wheel during rocking movement of said sheet.

- 10 7. In a machine for grinding the curved edge of a glass sheet or plate, a rotary grinding wheel positioned to rotate about a substantially horizontal axis, means arranged above said wheel for supporting the glass sheet to be ground on edge 15 in a vertical position, means for rocking said sup-

porting means and sheet carried thereby to move the curved edge of the sheet to be ground over and in engagement with said grinding wheel, a pressure roll mounted above the sheet supporting means, a pair of spaced, substantially horizontal cam members for supporting said pressure roll and having cammed upper edges, and means actuated by said sheet supporting means upon rocking movement thereof for moving the pressure roll along said cam members to engage the outer edge of the glass sheet and to be subsequently removed therefrom when said sheet supporting means reaches predetermined positions in its rocking movement.

HENRY O. KRANICH. 15
